UNITED STATES PATENT OFFICE.

ERNEST P. DARGIN, OF LOS ANGELES, CALIFORNIA, ASSIGNOR OF ONE-HALF TO
CHARLES S. BROWN, OF LOS ANGELES, CALIFORNIA.

FLUSHING APPARATUS FOR GARBAGE-CHUTES.

1,269,793.

Specification of Letters Patent. Patented June 18, 1918.

Application filed March 8, 1915. Serial No. 18,067.

To all whom it may concern:

Be it known that I, ERNEST P. DARGIN, a citizen of the United States, residing at Los Angeles, county of Los Angeles, and 5 State of California, have invented certain new and useful Improvements in Flushing Apparatus for Garbage-Chutes; and I do declare the following to be a full, clear, and exact description of the invention, such as 10 will enable others skilled in the art to which it appertains to make and use the same, reference being had to the accompanying drawings, and to the characters of reference marked thereon, which form a part of this 15 specification.

My invention relates to improvements in garbage chutes of the character employed in hotels, apartment houses, etc., and of the construction which extends the entire height 20 of the building and which has openings at each floor for the introduction of garbage. My present invention relates specifically to the means for automatically supplying water to these chutes for flushing purposes, whenever 25 a door is opened for the introduction of garbage. This invention discloses in its general characteristics those disclosed in my simultaneously pending application entitled Improvements in sanitary garbage chutes, 30 but the claims will be drawn to cover the flushing construction alone.

An important feature of my present construction consists in the location of the water pipe or conduit from which the supply is 35 taken at each floor, within a closed chamber or compartment adjacent the body of the chute and in communication therewith, whereby in case of a leaky valve, the escaping water will drain into the chute and therefore can do no damage to the building. Heretofore, so far as I am aware, chutes of 40 this character have had the valves for controlling the supply of water to the chute, exteriorly located or exposed in such a manner that leaks therefrom will pass to the floor of the building, and consequently, may result in doing great injury. Hence, one of the objects of my present invention is to obviate difficulties or accidents of this character. 45

Another feature consists in a special construction and arrangement of the door of the chute at each floor, whereby as the door is opened, the water is automatically turned on, while when the door is closed, it is turned 50

off. In the drawings, I have illustrated both a sliding and a hinged door for accomplishing this object.

Having briefly outlined my improvement, I will proceed to describe the same in detail, 60 reference being made to the accompanying drawing, in which is illustrated an embodiment thereof. In this drawing,—

Figure 1 is an elevation of a garbage chute of my improved construction, the same 65 being illustrated in use, enough of the chute being disclosed to permit the explanation of its use on any floor of a building, regardless of the number of floors.

Fig. 2 is a fragmentary elevation of the 70 construction, partly in section, the view being taken in the direction of arrow 2, Fig. 1, the parts being shown on a larger scale.

Fig. 3 is a similar view shown entirely 75 in elevation.

Fig. 4 is a vertical section taken on the line 4—5, Fig. 3, looking toward the right, and showing the door in the open position.

Fig. 5 is a similar view showing the door 80 in the closed position.

Fig. 6 is a view similar to Fig. 4, but showing another form of door construction. In this view, the door is shown open.

Fig. 7 is a view similar to Fig. 6, but showing the door closed. 85

The same reference characters indicate the same parts in all the views.

Referring first to Figs. 1 to 5, inclusive, let the numeral 5 designate the body of the chute, 6 its upper extremity extending above 90 the roof of the building, and open for ventilating purposes; 7 the garbage receptacle at the bottom of the chute; 8 a vertically movable hood arranged above the receptacle for closing purposes; 9 a lever for raising and 95 lowering the said hood; and 10 a floor of the building where the chute is located, the same being shown in section.

At a suitable distance above each floor 10, the chute is provided with an opening which 100 is normally closed by a door 12, which, as illustrated in the views now under consideration, is vertically movable in the grooves 13 of channel guides 14 and 15 with which the chute is equipped. The lower members 105 14 of these guides are built into the housing structure 16 applied to the chute adjacent each opening, while the upper members 15 of these guides are fastened, as by means of rivets 17, to the upper portion of the 110

housing structure 16 and extend above the same, being completely exposed or separated from the body of the chute, and are adapted to receive the opposite edges of the door 5 when the latter is lifted. The upper extremities of the guide members 15 are connected at the top by a transverse member 18, which is connected with the body of the chute as shown at 19, thus giving the guide members 15 the necessary strength and stability for the purpose.

Each door 12 is composed of two spaced plates, the outer plate being designated 20 and the inner plate 21, these plates being spaced at the top and bottom by transverse parts 22 and 23. This spacing of the plates 20 and 21 forms a chamber 24 within the door, into which protrudes a crank arm 25, whose outer extremity passes through an opening 26 formed in the inner wall of a housing 27 and whose outer wall 28 is exteriorly closed. Located within this housing 27 is a branch pipe 29 which passes through an opening 30 formed at the top of the housing 27 and is connected within the main water supply conduit 31 by means of a conduit member 32.

Within the chamber 33 of this housing, the branch pipe 29 is equipped with a valve 34, for controlling the supply of water to the chute as the door is opened. The outer extremity of the crank arm 25 is connected with this valve, the arrangement being such that when the door is closed or in the position shown in Figs. 2, 3 and 5, the valve is closed and the water cut off from the chute.

This crank arm, when the door is closed, is downwardly inclined from the valve at an angle of approximately 45 degrees and 40 is provided with a slot 35 which is entered by a pin 36 fast upon the door. Connected with this crank arm at a suitable point between its extremities, is one end of a spiral spring 39, whose upper extremity is connected with the part 22 at the top of the door, as shown at 37.

Consequently, as the door is raised, the crank arm 25 is carried upwardly therewith and imparts sufficient movement to 50 the valve 34 to open the same. The position of the crank arm when the door has reached its upward limit of movement is indicated by dotted lines in Fig. 2. In other words, when the crank arm 25 has reached 55 this position, the door cannot be raised farther, since the pin 36 engaging the slot 35 of the crank arm will not permit further movement. During this upward movement of the door, the spring 39 is stretched or 60 placed under tension, since the point 37 where the upper extremity of the spring 39 is connected with the door, must travel farther than the point 38 where this same spring is connected with the crank arm. In 65 other words, the point 37 must travel the

full distance between the full line position of the pin 36 in Fig. 2 and the dotted line position of the said pin in the same figure, while the point 38 can only travel the distance between the full line position of this 70 point in Fig. 2 and the dotted line position of the same point in the same figure, hence the spring 39 will be distended and its recoil action will aid in returning the door to its closed position, and also perform the 75 function of closing the valve 34.

The outer wall of the housing 27 is downwardly inclined at its lower extremity, as shown at 40, whereby any water which leaks into the chamber 33 of this housing 80 will pass downwardly into the chute through an opening 41 formed in the inner wall of the housing and communicating with the interior of the chute.

In the form of construction shown in 85 Figs. 6 and 7, a door 42 is hinged to a housing 43, which is offset from the body of the chute. Within this housing is located a branch pipe or conduit 44 in which a valve 45 is located. Connected with this valve 90 is a crank arm 46 with which one extremity of a rod 48 is pivotally connected, as shown at 47, the opposite extremity of the said rod being pivotally connected as shown at 49, with an inwardly projecting crank 95 arm 50, which is secured to the lower extremity of the door, and is raised by the opening movement of the door, as illustrated in Fig. 6. The door is normally held in the closed position by means of a weight 100 51 which is connected with the inner extremity of the crank arm 50 this weight also has the function of aiding in closing the door.

The housing structure in which the pipe 44, its valve and the means connected with 105 the door for operating the valve, are located, is offset from the body 5 of the chute in such a manner as to be out of the path of the garbage passing therethrough from the floors above any door and its connections. The lower extremity of the branch water supply pipe 44 extends transversely of the chute and parallel with the lower edge of the door, as shown at 52 in both forms of constructions, this pipe member being 110 perforated for the escape of water into the chute for flushing purposes. In the form of construction shown in Figs. 6 and 7, a deflecting plate 53 extends inwardly from the outer wall of the housing below 115 the door and above the transverse perforated member 52 of the water supply pipe, and prevents any water from escaping into the apartment when the door is open.

From the foregoing description, the use 125 and operation of my improved flushing attachment for garbage chutes will be readily understood. In the form shown in Figs. 1 to 5, inclusive, the door which is provided with a handle 54 for the purpose, is raised 130

for opening purposes, whereby it is carried upwardly so that its opposite vertical edges engage the channel members 15. The door is shown in this position in Fig. 4, the spring 5 39 being distended as illustrated in this view. The opening movement of the door actuates the crank arm 25, with which the said spring is connected, sufficiently to open the valve 34, whereby water is allowed to 10 enter the chute for flushing purposes.

In the form of construction shown in Figs. 6 and 7, the door is swung outwardly for opening purposes (see Fig. 6), and during this movement, the inner extremity of the 15 crank arm 50 is moved upwardly sufficiently to actuate the valve 45 for opening purposes, through the medium of the crank arm 46 and connecting rod 48. The act of closing either 20 form of door, reverses the movement of the valve piece and cuts off the water so that there shall be no escape of the water when the door is open.

Having thus described my invention, what I claim is,—

25 1. A garbage chute having a water supply pipe connected therewith to deliver water thereto, a valve in said pipe, a door slidably mounted, a crank arm connected at one extremity with the valve piece and at its 30 opposite extremity with the door by means of a pin and a slot, and a spring connecting the door with the crank arm at a point between the pin and the valve.

2. A garbage chute having a water supply 35 pipe connected therewith to deliver water thereto, a valve in said pipe, a door slidably mounted, a crank arm connected at one extremity with the valve piece and at its opposite extremity with the door by means of 40 a pin and a slot, and a spring connecting the door with the crank arm at a point between the pin and the valve, the crank arm and spring being housed within the door.

3. In a garbage chute, the combination 45 with the body of the chute, of a door slidably mounted thereon and arranged to normally close an inlet opening for garbage, a water pipe having a valve housed adjacent 50 the chute to deliver water escaping from the valve through a defect therein, into the chute, the door being composed of two spaced members, a crank arm connected with the valve piece and projecting into the space between the door members, a pin fast on the 55 door and passing through a slot formed in the crank arm of sufficient length to permit the opening of the valve as the door is opened by a vertical movement.

4. In a garbage chute the combination 60 with the body of the chute, of a door slidably mounted thereon and arranged to nor-

mally close an inlet opening for garbage, a water pipe having a valve housed adjacent the chute to deliver water escaping from the valve through a defect therein, into the 65 chute, the door being composed of two spaced members, a crank arm connected with the valve piece and projecting into the space between the door members, a pin fast on the door and passing through a slot formed in 70 the crank arm of sufficient length to permit the opening of the valve as the door is opened by a vertical movement, and a spring having one extremity connected with the upper part of the door and the other extremity connected with the crank arm between the slotted portion of the latter, and the valve.

5. In a garbage chute, the combination with the body of the chute, of a door slidably mounted thereon and arranged to normally close an inlet opening for garbage, a water pipe having a valve housed adjacent the chute to deliver water escaping from the valve through a defect therein, into the 80 chute, the door being composed of two spaced members, a crank arm connected with the valve piece and projecting into the space between the door members, a pin fast on the door and passing through a slot formed in 85 the crank arm of sufficient length to permit the opening of the valve as the door is opened by a vertical movement, and a spiral spring having one extremity connected with the top of the door and the other extremity 90 with the crank arm between the slotted portion of the latter and the valve, substantially as described.

6. A garbage chute having a water supply pipe connected therewith, a valve in said 100 pipe, said chute being provided with a door, a crank arm connected at one extremity with the valve piece and having its opposite extremity slidably connected with the door and means connecting the door with the crank 105 arm intermediate the extremities of the latter to facilitate the closing of the said door.

7. A garbage chute having a water supply pipe connected therewith, a valve in said pipe, the said chute being provided with a 110 door, means connecting the door with the valve, whereby opening and closing of the door opens and closes the valve, and means attached to said connecting means to facilitate closing the door.

In testimony whereof I affix my signature in presence of two witnesses.

ERNEST P. DARGIN.
